UNITED STATES PATENT OFFICE.

ALVAH C. SPENCER, OF BEVERLY, MASSACHUSETTS, ASSIGNOR TO UNITED SHOE MACHINERY COMPANY, OF PATERSON, NEW JERSEY, A CORPORATION OF NEW JERSEY.

HOLDDOWN.

1,150,072.

Specification of Letters Patent. Patented Aug. 17, 1915.

Application filed November 8, 1913. Serial No. 799,914.

To all whom it may concern:

Be it known that I, ALVAH C. SPENCER, a citizen of the United States, residing at Beverly, in the county of Essex and State 5 of Massachusetts, have invented certain Improvements in Holddowns, of which the following description, in connection with the accompanying drawings, is a specification, like reference characters on the drawings 10 indicating like parts in the several figures.

This invention relates to lasting machines of the bed type and particularly to work holding mechanisms or hold-downs for such machines. In these machines the shoe is 15 supported in inverted position and it has been found desirable to provide means to engage the forepart of the shoe bottom to hold the shoe upon the support or toe rest which is provided beneath that portion of the shoe. 20 It is also important to hold the toe end of the innersole down upon the last bottom to prevent it from being displaced during the toe lasting operation. For these purposes there has been provided a hold-down mechanism comprising a horizontal bar or carrier 25 movable into and out of operative position where it extends transversely across a shoe supported in the machine and which is adapted to be made, by suitable operating 30 mechanism, to apply pressure to the shoe over the ball portion of the last. On this carrier is mounted a foot member or finger extending forwardly from said end of the bar into position to hold the toe end of the 35 innersole down upon the last bottom, as more fully set forth in United States Letters Patent No. 1,120,822, granted December 15, 1914, on application of E. L. Keyes. The "spring" of the last, that is, the longitudinal 40 inclination of the forepart of the last relatively to the heel part, causes a wide variation in the relative vertical positions of the last bottom at the ball of the last and at the toe where the finger engages the innersole and therefore the toe holding fingers 45 have been made of resilient metal in order to adapt them to hold down an innersole on lasts having varying degrees of spring, the fingers yielding sufficiently to perform that 50 function in a last having a small amount of spring. It has proven difficult, however, so to construct and mount the innersole holding fingers that they will yield sufficiently for the purpose above pointed out and yet 55 hold the innersole down firmly, and as a

result the fingers in common use break frequently and such breakage is a source of delay and expense.

It is the object of this invention to provide a hold-down which will eliminate this 60 breakage of fingers and will provide means by which a substantially uniform holding pressure can be obtained at the toes of lasts having different degrees of spring.

An important feature of the invention 65 comprises in combination a carrier adapted to extend transversely of the last and a hold-down foot or finger mounted thereon, and means whereby the hold-down finger can be resiliently held for positioning movement in a vertical plane to adapt it to the 70 spring of different styles of lasts. Preferably the finger is given sufficient downward inclination to suit lasts of extreme spring while applying sufficient holding pressure 75 thereto, and resilient connections are provided between the finger and the carrier to permit the finger to yield to accommodate lasts having little or no spring. As herein shown, the foot member or finger is connected to the carrier by a bar which is mounted to rotate in the carrier about its longitudinal axis and has a resilient connection with the carrier which will permit it to 80 turn in response to upward pressure or resistance to downward movement of the free end of the inner sole engaging finger.

The invention will now be described in connection with the accompanying drawings and then in the claims will be pointed out 90 the combinations which it is intended to protect by this patent.

Figure 1 is a perspective view of the improved hold-down mechanism embodying this invention, together with the parts of 95 the bed lasting machine which are located adjacent to the toe; Fig. 2 is a detail, partly in section, of the connection of the hold-down finger to the rotatably mounted bar; Fig. 3 is a perspective view, partly in section, of the connection of the rotatably mounted finger carrying bar to the hold-down and operating mechanism; Fig. 4 is a 100 sectional detail of Fig. 3.

In the drawing, Fig. 1 shows at A the 105 wipers of a bed lasting machine with relation to the toe of a shoe being lasted. At B is shown the toe rest of the machine upon which the toe portion of the shoe rests and against which it is clamped by the holding 110

device. The hold-down comprises a vertical post 2 which is guided for vertical movement in the frame of the machine and which is depressed by means of a treadle, such, for example, as that shown and described in the patent to Keyes above referred to. Upon the upper end of the post 2 is a block 4 which is bored in directions at right angles to each other for the reception respectively of the vertical post 2 and a horizontal bar 6 which is rotatable upon its own axis in the block. The bar 6 carries at its forward end a finger 10 which is held in the bar by a stud 12, Fig. 2, which may be formed on or attached to the finger 10. The stud 12 is provided with a circumferential groove 14 which is engaged by a spring-pressed detent 16 sliding in the bar 6 for retaining the stud in place in the bar. The stud 12 has a tapered portion 15 which acts against the spring-pressed detent 16 to retract the same as the stud is pushed into place. The detent 16 may be retracted to permit removal of the stud and finger for interchange or replacement by means of a pin 20 which projects through a slot in the side of the bar, Fig. 1. The rear end of the bar which, as stated, is rotatable in the block 4, is provided with means, best shown in Figs. 3 and 4, for yieldingly turning it in the direction for holding the toe engaging portion of the finger 10 resiliently against the innersole. To this end the rear portion of the bar 6 projects through a recess in block 4, see Fig. 3, and has opposite sides flattened to form a non-rotatable connection with a lateral arm 24 in which there is a spring-pressed plunger 26, Fig. 4, which engages a recess in the bar 6. The lateral arm 24 is normally held down against a stop face 32 formed on the block 4 by a relatively stiff spring 34 secured to the block 4 at 36 and engaging the hooked end 38 of the arm 24. It will now be understood that downward movement of the post 2 will bring the end of the downwardly inclined finger 10 into contact with the toe portion of the innersole of the shoe, and that the finger will yield in a clockwise direction, the bar 6 being rotated and tension applied to the spring 34 as the member 24 is forced away from the stop 32. Evidently also the spring 34 may be extended sufficiently to take care of variations in the spring of the last without varying the tension on the spring to a substantial extent, the spring being normally under the minimum working tension required for lasts of extreme spring. The described separable connections between the bar 6 and the finger 10 and arm 24 permit any one of these parts of the hold-down device to be replaced without the expense of replacing the entire device. It will be noted that the bar 6 is in the nature of a rock-shaft having the arm 24 to which the power

is applied by the spring 34 and the hold-down finger 10 constituting the other arm for applying pressure yieldingly upon the toe of the innersole while the finger supporting end of the bar 6 is being brought into clamping engagement with the ball portion of the shoe.

It is obvious that various mechanical embodiments of this invention may be provided for accomplishing the objects stated and it is intended to embrace functional equivalents within the scope of the following claiming clauses which set forth what I regard as new and of my invention.

I claim—

1. In a hold-down for lasting machines, the combination with a hold-down finger, of a carrier therefor, connections between the carrier and the finger permitting rotation of the finger in a vertical plane, and means normally holding the finger against rotation but permitting the finger to turn when it is subjected to unusual strains.

2. A hold-down for lasting machines, having, in combination, a carrier, a hold-down finger mounted on the carrier to engage at its end the toe portion of a shoe innersole and having a downward inclination sufficient for lasts of extreme spring, and a mounting permitting the finger to yield to accommodate lasts having little or no spring.

3. A hold-down for lasting machines having, in combination, a finger for engaging the toe portion of a shoe, a mounting for the finger, a carrier for the mounting, and resilient means between the mounting and the carrier which will yield to excessive upward pressure upon the finger.

4. A hold-down for lasting machines, having a vertically movable post, a bar extending laterally of the shoe and rotatably mounted relatively to said post, a hold-down finger projecting laterally from one end of said bar, an arm projecting from the said bar, a stop for said arm, and resilient connections between the arm and the post for holding the arm down.

5. In a hold-down mechanism for lasting machines, the combination with a vertically movable post, of a hold-down device connected thereto for bodily movement into clamping engagement with the forepart of a shoe bottom and comprising a rock-shaft having an innersole toe engaging finger constituting one arm thereof, a second arm, and means acting through the second arm to hold the rock-shaft yieldingly in annular position for the finger to engage the toe of the innersole before the ball portion thereof is clamped.

6. In a hold-down mechanism for lasting machines, the combination with a vertically movable post, of a hold-down device connected thereto for bodily movement into clamping engagement with the forepart of

a shoe bottom and comprising a bar having an innersole engaging finger extending laterally from the bar and constructed and arranged to produce torsional strain on the bar by engaging the toe of the innersole in advance of the clamping engagement of the device with the ball of the shoe, said device including means located between the point of attachment of the finger to the bar and 10 said vertically movable part for resisting the torsional strain yieldingly.

7. In a hold-down mechanism for lasting machines, the combination with a vertically movable part, of a hold-down device connected thereto for bodily movement into clamping engagement with the forepart of a shoe and comprising a bar rotatably connected with said vertically movable part, a hold-down finger, a separable stud and 20 socket and spring detent connection between the bar and finger, an arm and spring through which rotary movement of the bar is resisted, and a separable connection between the bar and arm comprising opposed 25 flattened faces on the bar, a fork on the arm fitting said flattened faces and a spring detent having interlocking engagement with the arm and bar, all arranged to permit the bar, finger and arm to be separately replaced.

8. A lasting machine hold-down comprising, in combination, a carrier movable into and out of an operative position where it extends transversely across a shoe supported 35 in the lasting machine, a hold-down foot member supported on the carrier, and means constructed and arranged to resist yieldingly the movement of the foot member in a vertical plane required when the foot 40 member adapts itself during use to the spring of different styles of lasts.

9. A lasting machine hold-down comprising a carrier movable into and out of an operative position where it extends transversely across a shoe supported in the lasting machine, a foot member which is formed 45 at its front end to engage the toe of a welt shoe innersole against the inner side of the lip, a connector attaching the rear end of

said foot member to the carrier, and means 50 operating to hold the front end of the foot member normally depressed in a position where said member will engage the innersole first by said front end and will yield as the carrier is further depressed after 55 such first engagement of the foot member with the innersole occurs.

10. A lasting machine hold-down comprising a carrier movable into and out of an operative position where it extends transversely across a shoe supported in the lasting machine, a foot member which is formed at its front end to engage the toe of a welt shoe innersole, a connector to which the rear end of the foot member is attached and 60 which is rotatable in the carrier about an axis extending horizontally through the carrier, and a spring arranged between the connector and the carrier and operating to hold the front end of the foot member depressed 65 and to relieve strain on the connector and carrier when the front end of the foot member is forced upwardly relatively to the carrier by engagement with the work.

11. A lasting machine hold-down comprising a rigid carrier movable into and out of an operative position where it extends transversely across a shoe supported in the lasting machine, a resilient foot member which is formed at its front to engage the 80 toe of a shoe innersole and extends obliquely upward and backward to the carrier in a relation requiring it to be bent or sprung to allow holding down pressure to be applied to the shoe bottom back of the toe, a connector to which the foot member is attached and which is rotatable in the carrier, and a spring arranged to relieve the foot member, connector and carrier from excessive strain 85 when pressure is applied to the bottom of a 90 shoe back of the toe.

In testimony whereof I have signed my name to this specification in the presence of two subscribing witnesses.

ALVAH C. SPENCER.

Copies of this patent may be obtained for five cents each, by addressing the "Commissioner of Patents, Washington, D. C."

It is hereby certified that in Letters Patent No. 1,150,072, granted August 17, 1915, upon the application of Alvah C. Spencer, of Beverly, Massachusetts, for an improvement in "Holddowns," errors appear in the printed specification requiring correction as follows: Page 2, line 122, claim 5, for the word "annular" read *angular*; page 3, lines 10, 14, and 18, claims 6 and 7, for the word "part" read *post*; and that the said Letters Patent should be read with these corrections therein that the same may conform to the record of the case in the Patent Office.

Signed and sealed this 14th day of March, A. D., 1916.

[SEAL.]
